UNITED STATES PATENT OFFICE

DANIEL J. MACMILLAN, OF BROOKLYN, NEW YORK

PNEUMATIC DISPATCH CARRIER

Application filed April 4, 1930. Serial No. 411,485.

This invention has reference to the carriers used for conveying small articles, such as slips, documents or money, through tubes from one part of a building to another, or to remote locations, by causing a rapid current of air to flow through the tubes, by either pressure or exhaust.

The object of the present invention is to provide a simple form of carrier with indicating means, such as numbers, to show certain facts or data relative to the contents of the carrier, or to its sender, or to its use.

A further object of the invention is to provide a carrier of this nature with several indicating rings or bands that can be turned to form combinations of numerals; and which bands are provided with friction means to retain them in the adjusted positions.

20 In the accompanying drawings showing embodiments of my invention:—

Fig. 1 is a side elevation.

Fig. 2 is a longitudinal section.

Fig. 3 is an end view at the open end.

25 Fig. 4 is a partial view, cut away to show the friction bands for the rings.

Fig. 5 is a fragmentary view, showing the latter parts.

As shown in the drawing I provide an 30 inner tube 6, that is preferably formed of fiber having a comparatively thin wall, that is rigid, and which extends substantially the length of the carrier. At the middle portion of this inner tube I arranged a pair of flat 35 rings 7 and 8, that can be turned on the inner tube, and which carry numbers from 0 to 9 on the periphery of each, as shown. These can be relatively turned to indicate any number from 1 to 99.

40 The inner tube carries an outer tube in two portions, each extending from one of these rings to the end of the carrier. As shown an outer tube 9, of somewhat thicker wall and preferably formed of fiber, is placed on 45 the inner tube to extend from the ring 8 to the open end 10 of the carrier, and this outer tube is suitably secured to the inner tube, as by an adhesive between the contacting walls. A similar outer tube 11 is mounted

50 and secured on the inner tube 6 to extend

from the other ring 7 to the end of the carrier. This outer tube 11 is shown as projecting beyond the inner tube 6 at this end, to permit insertion of an end disk 12, inside of the said tube 11, and which abuts the end 55 of the inner tube 6, and suitably secured so that the disk 12 is flush with the end of the outer tube 11.

Carriers of this character are provided with bumper rings or bands at the ends as 60 15 and 16, that engage the walls of the tube through which the carrier passes, and may be formed of felt or similar soft material that will make a tight fit in the tube and prevent escape of the air, at the same time 65 have a kind of cushioning effect.

The outer tubes 9 and 11, or one of them, are provided with an indication such as a mark, 13 and 14, with which the numbers on the bands are brought to aline, when adjusted to the desired position. It will be understood that the number bands 7 and 8 turn on the inner tube independent of each other, but with sufficient friction to remain in adjusted positions relative to each other, 70 and to the indicating marks. It will be understood that these bands are practically flush with the outer tubes 9 and 11 on their faces, and will not engage the conveying tube. The carrier can be readily clasped by the 75 user at either end, and one or both of the number rings turned to bring the desired number, from 1 to 99, to register with the marks.

If desired, a friction device can be employed in connection with the number rings, and as shown a band ring 17 of very thin 80 spring metal, that is split and the ends slightly separated, are inserted between each of the bands 7 and 8, on the inner tube 6, 85 as clearly shown in Figs. 4 and 5. This will provide a very strong frictional engagement of the band with the inner tube, and retain the band in any position to which adjusted.

90 It will be understood that tubes of this character are comparatively simple and of low cost to produce, comprising merely the long inner tube, and the two outer tubes secured to the inner tube, with the friction 95 100

bands turning on the inner tube between the outer tubes; any desired form of closure may be employed, as well as any form of buffer bands at the ends. While the carrier 5 is shown having one end open, it can obviously be provided with a cap or closure for the other end well known in this art.

What I claim is:—

1. A dispatch carrier, comprising a rigid 10 inner tube of comparatively thin walls, a pair of comparatively narrow rings arranged to turn on the inner tube and provided with numerals on their periphery, a pair of outer tubes of thicker material than 15 the inner tubes, one mounted between the end of the carrier and the said rings at each end portion and secured to the inner tube, one of the outer tubes having a mark arranged to register with the numerals on 20 the rings, a closure for one end of the tube, a bumper ring mounted on each said outer tube at the end portion, and a split ring of very thin spring metal placed between each 25 said number ring and the inner tube to provide friction to retain the number ring in adjusted positions.

2. A dispatch carrier, comprising a rigid 30 inner tube of comparatively thin walls, a pair of comparatively narrow rings arranged to turn on the inner tube and provided with numerals on their periphery, a pair of outer tubes of thicker material than the inner tubes, one mounted between the end of the carrier and the said rings at 35 each end portion and secured to the inner tube, one of the outer tubes having a mark arranged to register with the numerals on the rings, a closure for one end of the tube, and a bumper ring mounted on each 40 said outer tube, at the end portion, said rings being substantially flush with the adjacent outer tubes.

3. A dispatch carrier, comprising a rigid 45 inner tube of comparatively thin walls, a pair of comparatively narrow rings arranged to turn on the inner tube and provided with numerals on their periphery, a pair of outer tubes of thicker material than the inner tubes, one mounted between the 50 end of the carrier and the said rings at each end portion and secured to the inner tube, one of the outer tubes having a mark arranged to register with the numerals on the rings, a closure for one end of the tube, a 55 bumper ring mounted on each said outer tube at the end portion, and a split ring of very thin spring metal placed between each said number ring and the inner tube to provide friction to retain the number ring in 60 an adjusted position, said rings being substantially flush with the adjacent outer tubes.

4. A dispatch carrier having a tubular body provided with a circumferential groove intermediate its ends and having an index 65 adjacent said groove, a plurality of member

rings mounted in said groove side by side and adapted for independent movement circumferentially of the tube, and a thin arcuate split friction spring interposed between each ring and the bottom of the 70 groove.

Signed at New York city, N. Y. on March 31, 1930.
